LEONARD BAENZIGER, OF ABINGTON, MASSACHUSETTS, ASSIGNOR TO ACME ELECTRIC MANUFACTURING COMPANY, OF CHELSEA, MASSACHUSETTS, A CORPORATION OF MASSACHUSETTS.

FUSE PLUG.

Application filed February 23, 1927. Serial No. 170,089.

REISSUED

This invention relates to fuse plugs.

The object of my invention is the production of a fuse plug that will not break or shatter when it blows out.

5 This invention is an improvement on my invention, an application for which was filed January 2, 1926, Serial No. 78,988, in which the construction of the fuse was described.

This invention relates to a method of construction by which the hot gas produced when a fuse blows out, will be prevented from coming in contact with the walls of the glass, preventing the breaking or shattering of the glass.

15 The invention will be hereinafter considered in detail and specifically claimed. Reference will now be had to the drawing forming a part of this application, wherein there is illustrated a preferred embodiment of my 20 invention, but it is understood that the elements thereof can be varied or changed as for shape, size, or form without departing from the spirit of the invention.

Fig. 1 is a vertical section through the center of the fuse.

Fig. 2 is a view of the fuse with the copper shell, broken away to show a certain part of its construction.

10 designates a fuse having a top member 30 11 made of a colorless, transparent material such as glass. The bottom of the glass top has a rectangular indenture 12. The bottom part 12' is made of porcelain with a shoulder 13 and a round extension 14 which fits 35 into the inside of the glass top. The shoulder 13 carries an extension 15 which fits into the opening 12. A brass screw thread fits around the threads on the outside of the glass top 11. A cylinder 16 made of non- 40 conducting and preferable insulating mate-

rial fits snugly between the extension 14 and the sides of the top member 11.

The fusing member 17 is connected at the bottom in the usual manner, forming the loop 18, and follows along the insulating material 16, into and through the opening 12 and along the recess 19 in the side of the glass top, where it is connected with the brass thread and glass in the usual manner. 45

From this construction it will be seen that the presence of cylinder 16 prevents the fusing member from coming in contact with the side of the glass. Also the hot gases will be prevented from coming in contact with the sides of the glass, and shattering of the 55 glass will thereby be eliminated.

Having described my invention, what I claim is:

1. A fuse plug comprising a hollow glass body closed at one end, a fuse therein visible through said closed end, and means to prevent hot gases from coming in contact with the side walls of said glass body comprising a removable sleeve of non-conducting material positioned within said glass 60 body in contiguous relation with the side walls thereof and spaced from the major portion of the fuse. 65

2. A fuse plug comprising a hollow transparent body, a fuse therein, an insulation plug closing the bottom of said body and having a projection extending therein, and means to prevent hot gases from coming in contact with the walls of said body comprising a sleeve of non-conducting material positioned within said body between the walls thereof and the periphery of the projection of said plug in contiguous relation with the walls of said body. 75

LEONARD BAENZIGER.
